UNITED STATES PATENT OFFICE.

HARRY W. KRANZ AND JOHN LUKES, OF CLEVELAND, OHIO, ASSIGNEES TO THE HYDRAULIC PRESSED STEEL COMPANY, OF CLEVELAND, OHIO, A CORPORATION OF OHIO.

FLUID-OPERATED BAND-PUNCHING MACHINE.

Application filed June 28, 1920. Serial No. 392,455.

To all whom it may concern:

Be it known that we, HARRY W. KRANZ and JOHN LUKES, citizens of the United States, residing at Cleveland, in the county 5 of Cuyahoga and State of Ohio, have invented a certain new and useful Improvement in Fluid-Operated Band-Punching Machines, of which the following is a full, clear, and exact description, reference being 10 had to the accompanying drawings.

This invention relates generally to machines for punching rims, fans and more particularly to a fluid operated machine for punching felly bands.

15 In the manufacture of automobile wheels it is customary to place a sheet metal felly band upon the wooden felly in the wheel body and this felly band is ordinarily formed with a base portion, an inwardly 20 projecting flange portion which engages the outer face of the wooden felly while at the inner edge the felly band is somewhat thickened and provided with a beveled or inclined flange against which the mountable 25 tire carrying rim is intended to be forced. These felly bands are of course perforated or formed with an opening for the valve stem of the tire and in some instances metallic boxes or plates are riveted to the 30 outer face of the felly band upon opposite sides of the valve stem hole and the object 35 of the present invention is to provide a machine which will at a single operation punch the valve stem hole and also punch holes upon opposite sides thereof to receive the 40 rivets which fasten the plates or blocks to the felly band.

In addition to providing a fluid operating 45 machine which will punch all of the holes at a single operation it is also the object of this invention to provide for the quick and easier removal of the punches and guides in case either should become impaired, or in case it is desired to change or alter the relative position of the various holes.

A still further object is to provide a machine embodying these characteristic features which shall consist of a minimum number 50 of strong and durable parts, easily manipulated to perform their various functions.

With these objects in view and certain others which will become apparent as the description proceeds, the invention consists 55 in the novel features of construction and in

the manner of combining or arranging the same all of which will be fully described hereinafter and pointed out in the claims.

In the drawings forming a part of this specification, Fig. 1 is a side elevation of a 60 fluid operated punching machine constructed in accordance with our invention; Fig. 2 is a top plan view of the same; Fig. 3 is an end view; Fig. 4 is a central longitudinal sectional view; Fig. 5 is a detail perspective view of the guide block; Fig. 6 is a detail perspective view of one of the punches and plunger carrying the same and Fig. 7 is a detail perspective view of the piston and yoke carrying the punch plungers. Referring 65 to the drawings, 10 indicates a stationary base which may be of any desired size and shape and to which is securely bolted the guide block 11 said guide block having laterally projecting ears 12 through which 70 the fastening bolts pass for the purpose of connecting said block to the base of the machine. One end of said block 11 is cut away as shown and to this cutaway there is secured the double cylinder block 13. 75

In the other end of the block there is cut a curved guideway 14 which is intended to receive a felly band or rim 15 which is to be punched and the convex wall of this guideway 14 is recessed as shown at 16 to receive 80 the die block 17 therein.

The guide block is also provided with a central guideway 18 which is preferably arranged along the longitudinal axis of the block and upon each side of the central 85 guideway 18 are the inclined guideways 19 said guideways extending into and communicating with the curved guideway 14 in which the felly band or rim is to be placed. Working in the central guideway 18 is a 90 plunger 20 carrying a punch 21 at its end and which is intended to punch the valve stem hole in the felly band, and in each guideway 19 is a plunger 22 carrying a plurality of punches 23 at its outer end for 95 the purpose of punching the rivet holes in the felly band upon opposite sides of the valve stem hole. The central punch 20 is pivoted between lugs 24 while the plungers 22 are pivoted between the lugs 25, the lugs 100 24 extending longitudinally from the face of the yoke 26 while the lugs 25 project laterally in opposite directions from the sides of the said yoke. The yoke 26 is rigidly 105 connected to a piston 27 working in the cyl- 110

inder 28 of the double cylinder block 13, fluid pressure being applied to said piston 27 through the pipe 29 and in the cylinder 30 formed in the opposite end of the cylinder block there is a piston 31 connected to a yoke 32, the yoke 32 and yoke 26 being connected by tie rods 33 and fluid pressure is applied to the cylinder 30 by means of the pipe 34. It will be noted that the diameter 10 of the cylinder 28 and its piston 27 is considerable in excess of the diameter of the cylinder 30 and its piston 31, the piston 27 being a power piston for the purpose of effecting the punching operations whereas 15 the piston 31 operates for the purpose of leading the piston 27 and withdrawing the punches.

In operation the felly band or rim 15 is placed into guideway 14 and fluid pressure 20 is applied to the cylinder 28 acting upon the piston 27 forcing the yoke 26 toward the felly band or rim carrying with it the central plunger 20 and side plungers 22 all of which are brought into engagement with the 25 felly band or rim at one time owing to the angular disposition of the side punches which is made to conform to the curvature of the felly band or rim and consequently the valve stem hole and the rivet holes are 30 all punched in one and the same operation. Then by the application of fluid pressure in the reverse direction the punches are withdrawn and the felly band or rim can be removed and another one inserted ready to be 35 punched. The forward end of each plunger is slotted or recessed longitudinally as shown at 35 and also transversely as shown at 36, a longitudinal slot or recess being adapted to receive the shank 37 of the punch while 40 the foot piece 38 thereof fits into the transverse slot and a cap piece 39 is bolted down over the shank portion and retains the same in place. The shank 37 carries a head 41 and this head 40 is formed with a recess 41 into which the enlarged end of the punch proper is inserted and the perforated plate 42 is fastened to the face of the head 40 for the purpose of retaining the punches proper 45 within the head. By means of these special features of construction it is obvious that if 50 one or more of the punches should become impaired they can be quickly and easily removed and replaced and in case it is desired to remove the entire head and replace the 55 same with another head bearing punches differently arranged it can be quickly and easily accomplished by removing the cap piece 39 lifting out the shank 37 and replacing another head.

60 The guide block 11 is also formed with a longitudinal guideway 43 in which the tie rod 33 and the lower end of the yoke 36 works and if desired, the double cylinder block can be provided with a slotted lug 44 65 to guide the upper tie rod. The block 11 is

also provided with post or lug portions 45 to which the horizontal tie rods 46 are connected the opposite ends of said tie rods being connected to a stationary yoke 47 contacting with the rear end of the double cylinder block as most clearly shown in Figs. 1, 2 and 4.

It will thus be seen that we provide a simple, durable and efficient fluid operated mechanism for simultaneously punching the 75 valve stem and rivet holes in a felly band or rim and it will also be noted that the various punches and plungers operating the same can be quickly and easily changed or altered when necessary or desirable.

Having thus described our invention, what we claim is:

1. In a device of the kind described, the combination with a guide block having a fluid pressure cylinder connected thereto, of pistons working in said cylinder block, said block having a circumferential guide way to receive a rim or band, and one or more substantially longitudinal guide ways each adapted to receive a punch carrying plunger and means connecting said plunger or plungers with said pistons.

2. In a device of the kind described, the combination with a block having a rim or band guide way, of a cylinder block and a piston working therein, a yoke operatively connected with said piston and one or more punch carrying plungers connected to said yoke and movable toward and away from 95 said rim or band guide way.

3. In a device of the kind described, the combination with a block having a band and one or more plunger guide ways, of a cylinder block having one or more pistons working therein, a plunger in each plunger guide way, a yoke to which said plunger or plungers are connected and means connecting said yoke and piston.

4. In a device of the kind described, the combination with a guide block, of a cylinder block connected thereto, pistons working in said cylinder block, a yoke operatively connected to said pistons, a longitudinal plunger and lateral converging plungers connected to said yoke, said plungers working in guide ways in said guide block, said block also having a band guide provided with a die recess.

5. In a device of the kind described, the combination with a plunger having longitudinal and transverse slots at the forward end thereof, of a shank having a foot and head piece, a cap for holding the shank to the plunger, and one or more punches detachably connected to the head.

6. In a device of the kind described, the combination with a plunger having longitudinal and transverse slots at the forward end thereof, of a shank having a foot and head piece, a cap for holding the shank to 130

the plunger, one or more punches having enlarged inner ends and a perforated plate attached to the head for securing said punch or punches to the head.

5. 7. In a device of the kind described, the combination with a plunger having a longitudinal and transverse slot in the forward end, of a shank having a foot and head portion connected thereto, a cap piece, holding

the shank in said longitudinal slot, one or 10 more punches having enlarged inner ends, and a perforated plate attached to said head and securing said punch or punches in place.

In testimony whereof, we hereunto affix our signatures.

HARRY W. KRANZ.
JOHN LUKES.
